UNITED STATES PATENT OFFICE.

GEORGE B. MCCOY, OF STAMPER'S CREEK, INDIANA.

DOUBLE-ACTION PUMP.

SPECIFICATION forming part of Letters Patent No. 276,614, dated May 1, 1883.

Application filed April 7, 1882. (No model.)

To all whom it may concern:

Be it known that I, GEORGE B. MCCOY, of Stamper's Creek, in the county of Orange and State of Indiana, have invented a new and useful Improvement in Double-Action Pumps, which improvement is fully set forth in the following specification and accompanying drawing; in which the figure is a vertical sectional view of the improved pump.

10 The object of my invention is to provide an improved method of manufacturing pumps; and it consists in having two vertical cylinders secured to a horizontal cylinder beneath, and riveted near the upper end by a pipe having 15 a discharge-spout, the lower cylinder having a supply-port, and all the parts forming the piston, cylinders, discharge and supply ports united to each other by screw-threads, so that the various parts may be readily duplicated, 20 or so that the pump may be quickly taken apart and put together.

In the accompanying drawing, A represents a suitable frame or standards, united at the upper ends by a cross beam or arch, B. At 25 the base, between the standards, is a horizontal cylinder, C, having centrally on the under side a supply-pipe, D. Near each end, on the upper side, are located the vertical piston-cylinders E. Near the upper ends is a cross pipe or tube, F, 30 and leading from the upper side preferably of this connecting-tube is a discharge spout or pipe, G.

H is the piston-head, having the apertures I and the upwardly-opening valves J.

35 K K are the piston-rods, hinged at the upper ends to the connecting-rods L, which latter are in turn hinged to the lever M. This lever is pivoted to the beam or arch B at a point midway between the connecting-rods L.

40 N is the head of the cylinder, screw-threaded to fit the screw-threaded aperture of the cylinder E. The upper side of this head is provided centrally with a cavity, O, to receive

packing, and P is a follower which rests on the packing. The follower is in turn held in the 45 cavity by means of the cap Q, which is adapted to screw onto the upper end of the head N.

The horizontal cylinder C, the vertical cylinder E, and the connecting-tube F are each provided with flanges R at their connecting-points, and screw-threaded within. The supply-pipe D, cylinders E, connecting-tube F, and discharge-spout G are each screw-threaded on the ends to fit the screw-threaded flanges at the various points.

55 It will thus be seen that the pump constructed in this manner is made in independent parts united by screw-threads, as shown, enabling the same to be readily taken apart or set up.

60 It is obvious that the cylinders and connecting-tubes can be made of either wood or metal, united substantially in the manner shown.

65 S are the valves at the lower ends of the piston-cylinders; but these, with the valves in the piston-head and the piston, form no part of my invention.

70 I am aware it is not new to construct a pump with two upright cylinders having the cross-pipes, valves, and pistons, and my invention has no reference thereto; but

75 What I claim is—

A pump having the several parts, consisting of the supply-pipe D, horizontal cylinder C, piston-cylinders E E', connecting-pipe F, and discharge-tube G, constructed independently of each other and united by screw-threads, substantially as and for the purpose herein shown.

80 In testimony that I claim the foregoing I have hereunto set my hand, this 29th day of March, 1882, in the presence of witnesses.

GEORGE B. MCCOY.
